CLAIM

The ornamental design for a rear fairing for a snowmobile, as shown and described.

DESCRIPTION

FIG. 1 is a left-rear perspective view of a rear fairing for a snowmobile showing our new design;

FIG. 2 is a rear elevational view thereof;

FIG. 3 is a left-side elevational thereof, the right side being a mirror image;

FIG. 4 is a top plan view thereof; and,

FIG. 5 is a bottom plan view thereof.

The broken line showings are for illustrative purposes only and form no part of the claimed design.
